ELECTRICAL RELAY

John N. Reynolds, Princeton, N. J.

Application January 17, 1941, Serial No. 374,839

15 Claims. (Cl. 200—104)

This invention relates to relay devices which are adapted for making and breaking electrical circuits, and more especially circuits used in connection with telephone work. The subject matter of the present invention is in the nature of an improvement on the invention disclosed in my U. S. Patent No. 2,248,584, issued July 8, 1941. In said patent a relay is disclosed in which a plurality of movable contact springs are actuated by a rotatable actuating plate which in turn is actuated by the armature of a two pole magnet. The movable contact springs cooperate with fixed contact springs which are supported in stationary positions to make or break circuits or to transfer circuits. The present application is a division of patent application Serial No. 289,534, filed in my name on August 11, 1939, now Patent No. 2,238,077, issued April 15, 1941.

It is a main object of the present invention to provide a relay of the type described in which the movable contact springs are operated together by means of a rotatable actuating plate supported by the armature of the electromagnet, the armature being arranged to oscillate about a region on a stationary surface which is in substantial alignment with the axis of rotation of the rotatable actuating plate. In the preferred embodiment of the invention, the electromagnet is so shaped and arranged that one of the legs thereof provides such a stationary surface providing an axis of rotation for the armature.

In pursuance of a further object of the invention, the surface of the armature which bears against the leg of the magnet is non-planar and in one embodiment of the invention is formed by two flat faces disposed at an obtuse angle to each other. In another illustrated embodiment of the invention, the face of the armature which bears against the leg of the electromagnet is convexly curved, so that the armature has a slight rolling motion along the face of the magnet leg.

A cognate object of the invention lies in the provision of means for preventing the displacement of the pivotal supporting region of the armature from its proper position of engagement with the leg of the magnet. Such means in one illustrated embodiment of the invention comprises a projecting ridge formed integral with the armature, a suitable opening in the leg of the magnet being provided to receive such ridge. In another illustrated embodiment of the invention, the face of the armature is provided with a pair of spaced openings formed therein, a pair of pins being provided in the leg of the magnet which fit loosely into said spaced openings and

retain the armature in position without interfering with its rolling action along the leg of the magnet. Associated with the latter form of the invention, novel means is provided to limit the return movement of the armature, such means preferably comprising a pin which is carried by the armature and arranged to come into engagement with a leg of the electromagnet.

A still further object of the invention is to provide an armature serving to support the rotatable plate which actuates the movable contact springs, such plate being preferably formed of moldable plastic material and the armature being molded therein at the time the plate is molded.

Further objects of the invention will become apparent to those skilled in the art as the description thereof proceeds. For a better understanding of the invention, however, reference is made to the accompanying drawings, in which—

Fig. 1 is a front view of a multi-contact relay device embodying the invention showing also a portion of a supporting panel adapted to support a plurality of the relays;

Fig. 2 is a longitudinal sectional view of the relay shown in Fig. 1;

Fig. 3 is a fragmentary view, partly in section, showing the armature of the relay of Fig. 1 and a portion of the magnet which supports it;

Fig. 4 is a fragmentary view, partly in section, of an armature and the support of Fig. 5;

Fig. 5 is a fragmentary view from the left of Fig. 4 of the armature support;

Fig. 6 is a front view of a relay device embodying a modified form of the invention;

Fig. 7 is a top plan view of a relay showing another modified form of the invention, the contact springs being omitted;

Fig. 8 is a front view of the relay shown in Fig. 7;

Fig. 9 is a view of the magnet of Fig. 7 upon development into a single plane; and

Fig. 10 is a fragmentary view, partly in section, showing one set of the relay contact springs and portions of the base, back stop plate and contact spring actuating plate of the relay of Fig. 7.

In the embodiment of the invention shown in Figs. 1, 2 and 3, the base 65 of the relay is provided with parallel end portions 66 and arcuate shaped upper and lower end portions 67, the base being formed of moldable insulation material in which the contact springs 10a and 11a are molded, and in which is also molded the end of the magnet 68 having the parallel disposed rectangular shaped legs 69 and 70. The energizing coil 71 is mounted on the magnet leg 70 and ex-

tends into an opening 72 provided in the front of the base 65. Also molded in base 65 are the contact terminals 26a and 27a which are connected to the ends of coil 71 by the leads 24a and 25a. The relay is preferably attached to a main supporting panel 73 through the medium of the magnet 68, the panel being formed of metal which is provided with similar openings 74, through which pass the rear ends of the relay contact springs 10a, 11a as shown in Fig. 2. The magnet is secured in position on panel 73 by the screw 75, which passes into a threaded opening 76, formed in the end of magnet 68. By means of this arrangement, a substantial amount of any heat which may be generated in the coil 71 is transferred to the supporting panel 73 by conduction, thereby maintaining the coil and relay at a safe operating temperature. In this embodiment of the invention the contact springs 11a are stationary and are seated in narrow peripheral notches 77, formed in a stationary supporting plate 78, formed of insulation material and secured to the magnet legs 69 and 70. One side of plate 78 is preferably cut away on a circular arc as indicated at 79 in Fig. 1. The movable relay contact springs 10a are cut away on their inner edges as indicated at 20a for the purpose of readily clearing the plate 78.

For the purpose of actuating the movable contact springs 10a, a contact spring actuating plate 80 is provided with a series of narrow slits 81 in its periphery, in which the outer ends of the contact springs 10a are seated. Plate 80 is preferably formed of molded insulation material, and molded into its rear surface is an armature 82 of the form shown in Figs. 1 and 3 and having an outwardly extending toe 83, adapted to be drawn towards pole-piece 69. At its rear end the armature is provided with a curved face 84 adapted for free rolling engagement along the flat surface of the magnet leg 70. Two spaced-apart tapered openings 85 are formed in the curved face 84 of the armature, into which are loosely fitted a pair of pins 86, which are secured in and extend a slight distance from magnet leg 70. The fit of these pins in the tapered holes 85 is such as to afford a certain degree of support to the armature 82 on magnet leg 70 but at the same time to permit a rolling movement of the armature on its curved face 84. In order to secure the armature in its proper operating position, it is provided with a notch or aperture 87 in which one end of a curved spring 88 presses the armature against the magnet leg 70, the right hand end of spring 88, Fig. 1, being in clamping engagement with the rear surface of the leg 70, as shown. For the purpose of decreasing the mass and inertia of the actuating plate 80, its opposite sides may be cut away to provide circular edges 89 as indicated in Fig. 1. Armature 82 is provided with a pin 90 which engages the magnet leg 69 to limit the return motion of the armature. By bending the pin 90 slightly, the extent of motion of the armature and actuating plate 80 may be adjusted to a desired amount.

A number of relays similar to the one described may be mounted within a small space on the supporting panel 73, since the periphery of the stationary plate 78 of the next adjacent relay may be disposed close to and extend into the cut-out portion 79 of the relay shown in Fig. 1. The provision of this cut-out in each stationary plate 78 affords means whereby the relays may

be spaced more closely together on the supporting panel.

In the operation of the relay described, the passage of an electrical current through coil 71 causes magnetic lines of force to pass through the magnet legs 69, 70 and armature 82, causing the toe piece 83 to be drawn over against the surface of leg 69. In this movement the face 84 of the armature has a rolling motion on the surface of magnet leg 70 with which it is in engagement, so that substantially no friction results from the motion of the armature. Since the armature is connected to contact spring actuating plate 80, this plate rotates and causes the ends of contact springs 10a to rotate through a small angle and engage the stationary contact springs 11a. The armature is so positioned on rotatable plate 80 that the axis of rotation of the plate coincides with the center of rotation of the armature on the surface of magnet leg 70. The stationary supporting plate 78 forms a backstop for the contact springs 11a and prevents them from following the contact springs 10a and coming into engagement with the next adjacent set of contact springs which might result in the opening or closing of circuits not intended to be operated. While the armature has been shown connected to the front plate 80, it will be understood that it may be connected to the rear plate 78 if desired, in which case the movable contact springs 10a would be connected to the periphery of this plate, which would be provided with a large central opening to clear the magnet legs 69, 70. The stationary contact springs 11a would be connected to the stationary front plate 80 which could be mounted on the outer ends of magnet legs 69 and 70. In this form of the invention the contact springs are arranged in two oppositely disposed groups, one group at the top of the relay and the other group at the bottom.

Instead of providing the magnet leg 70 with pins such as 86 for positioning the armature, this leg may be provided (see Figs. 4 and 5) with an elongated V-shaped aperture 91 adapted to receive a similar V-shaped projection 92 formed on armature 82' and which fits loosely therein. In this modification, the rear of the armature is provided with the two flat inclined faces 91a and 91b, the face 91a lying in contact with the surface of magnet leg 70 when the magnet is unenergized, as shown in Fig. 4. Upon passage of an electrical current through coil 71, the toe 83' of the armature is drawn over against leg 69, the armature rotating about the rear edge 92' of projection 92 as a point of pivotal support until its face 91b lies adjacent to the surface of magnet leg 70. In this modification also, the center of rotation 92' of the armature is preferably arranged to be in alignment with the axis of rotation of the contact spring actuating plate 80.

The modification shown in Fig. 6 is generally similar to that shown and described in connection with Figs. 1, 2 and 3 but is intended for the control of a smaller number of circuits, the sets of contact springs being arranged in a single group herein shown located at the bottom of the relay. For this purpose the relay base 65a is made lower, the straight ends 66a of the base extending up only to the middle of the relay and being connected by the circular peripheral face 93. Also the rotatable contact spring actuating plate 80a and the stationary back stop plate 78a extend only a slight distance past the middle of the relay, being terminated in the flat

faces 94 and 95 respectively. In this modification the notch 87 in the armature and spring 88 of Figs. 1 and 2 are omitted and the armature 82a is maintained in proper position against the pins 86a and with its front surface 84a in contact with the surface of magnet leg 70a by means of an adjustable screw 96 which engages a threaded bore 97 in magnet leg 69a. Screw 96 is so adjusted that it bears rather loosely against armature 82a so as not to interfere with its free movement under the action of the magnet. Screw 96 is preferably made of brass or other non-magnetic material so as not to conduct the magnetic flux from the central portion of the armature to the magnet leg 69a and thereby possibly interfere with the proper operation of the relay. Passage of an electrical current through coil 71a causes armature 82a to roll along the surface of leg 70a and rotate the actuating plate 80a through a small angle, thereby causing the movable contact springs 10b to engage the fixed contact springs 11b.

The modification shown in Figs. 7 to 10 has the same general arrangement as that shown and described in connection with Fig. 6, the relay being supported on the panel 73 by a securing screw 75 in the manner above described in connection with Figs. 1 and 2. In this construction the back stop plate 78b for the fixed contact springs 11c is secured to magnet leg 70b, the movable contact springs 10c being cut away, as indicated at 20c, Fig. 10, so as to clear the stop plate 78b. The armature 82b extends forwardly of the movable contact spring actuating plate 80b and is preferably molded therein, the fixed contact springs 11c being cut away, as indicated at 20d, Fig. 10, so as to clear the plate 80b.

For the purpose of pivotally supporting the armature 82b and the plate 80b, the end of magnet leg 69b is provided with a slot 98 adapted to receive one leg 99 of a generally U-shaped spring 100 which has its end bent, as indicated at 101b, to enter a small bore 102, Fig. 9, provided at the rear end of the slot 98. The end of magnet leg 70b is provided with a V-shaped slot 91, Fig. 9, into which extends a V-shaped projection 92, formed on the armature in the manner above described in connection with Figs. 4 and 5, the surface of the armature adjacent magnet leg 70b being provided with the inclined faces 91a and 91b. The other leg 99' of spring 100 has its end bent over at right angles, as indicated at 103 to freely enter a bore 104 provided in the left face of the armature, the point of engagement 105 of the end portion 103 of the spring with the armature being closely adjacent to the pivotal supporting edge 92' of the armature. The construction described provides the desirable advantages that substantially no motion of the spring 100 occurs during the motion of the armature and the friction is reduced to a minimum.

In this construction, in addition to the flat top face 94a, the side faces 106 of the contact spring actuating plate 80b may be formed straight and parallel, as shown in Fig. 8, curving out slightly at their lower ends, as shown. Also the center portion of plate 80b may be cut away, as shown, to provide a generally oval shaped opening 107 through which magnet leg 70b passes with an adequate amount of clearance. While the relay has been shown secured in a horizontal position on panel 73 with the body of armature 82b disposed at the left of its pivotal supporting edge 92', it will be understood that it is also operative when mounted with the armature body dis-

posed above or below its point of pivotal support. Passage of an electrical current through coil 71a causes the armature 82b to rotate about its point of pivotal support 92' which is in alignment with the axis of rotation of the actuating plate 80b, causing this plate to rotate through a small angle and move the movable contact springs 10c into engagement with the fixed contact springs 11c.

10 I have described what I believe to be the best embodiments of my invention. I do not wish, however, to be confined to the embodiments shown, but what I desire to cover by Letters Patent is set forth in the appended claims.

15 I claim:

1. A relay device comprising in combination, an electromagnet provided with a pair of parallel spaced apart legs and an armature formed of para-magnetic material disposed between said 20 legs and having a non-planar supporting face, a stationary surface, a plurality of fixed contact springs, a plurality of movable contact springs adapted for engagement with the fixed contact springs, a rotatable actuating plate connected to 25 said armature, means connecting said actuating plate with the movable contact springs and means cooperating with the armature and arranged upon the passage of current through the coil of the electromagnet to cause the armature 30 to rock about a region on said stationary surface which coincides substantially with the axis of rotation of said actuating plate and the end of the armature to come into engagement with the end of one of the said magnet legs whereby the 35 armature provides a return path of low reluctance for the magnetic flux between the ends of said magnet legs.

2. A relay device in the combination as set forth in claim 1, in which the rotatable actuating plate is formed of moldable insulation material and the armature is molded in the said insulation material.

3. A relay device in the combination as set forth in claim 1, in which the stationary surface 45 is formed by the face of a leg of the electromagnet.

4. A relay device in the combination as set forth in claim 1, in which a yielding means engages the armature to bias its supporting face into engagement with the stationary surface.

5. A relay device in the combination as set forth in claim 1, in which the face of the armature opposite its supporting face is provided with a recess and a spring has one of its ends seated in 55 said recess and its other end in engagement with the electromagnet.

6. A relay device in the combination as set forth in claim 1, in which an elongated projecting ridge extends from the supporting face of the armature and a leg of the electromagnet is provided with a recess shaped to receive said projecting ridge.

7. A relay device in the combination as set forth in claim 1, in which the supporting face of the armature is formed of two substantially flat surfaces arranged at an angle to each other, the region between said surfaces forming a point of pivotal support for the armature.

8. A relay device in the combination as set forth in claim 1, in which the supporting face of the armature is formed of two substantially flat surfaces arranged at an angle to each other, the region between said surfaces forming a point of pivotal support for the armature and one of said surfaces being arranged to come into engagement

with the stationary surface to limit the return movement of the armature.

9. A relay device in the combination as set forth in claim 1, in which the face of the armature opposite to its supporting face is provided with a bore which terminates closely adjacent to the supporting face and a spring having one of its ends in engagement with the inner end wall of the bore.

10. A relay device in the combination as set forth in claim 1, in which the electromagnet is provided with a pair of pole pieces, one of said pole pieces being provided with an aperture therein, and a U-shaped spring having one leg seated in said aperture and its other leg in engagement with said armature at a point thereof closely adjacent to said stationary surface.

11. A relay device in the combination as set forth in claim 1, in which an elongated notch is formed in said stationary surface and the supporting face of the armature is formed of two substantially flat surfaces arranged at an acute angle to each other and a projecting ridge on said armature intermediate the flat surfaces thereof, said ridge fitting loosely into said elongated notch.

12. A relay device in the combination as set forth in claim 1, in which the supporting face of the armature is convexly curved and arranged

for rolling engagement with said stationary surface.

13. A relay device in the combination as set forth in claim 1, in which at least two spaced apertures are provided in the supporting face of the armature and the electromagnet is provided with pins projecting and loosely fitting into said spaced apertures.

14. A relay device in the combination as set forth in claim 1, in which the armature is provided with a projecting pin adapted to come into engagement with a leg of the electromagnet so as to limit the return movement of the armature.

15. A relay comprising U-shaped stationary magnet legs formed of para-magnetic material, an energizing coil disposed on one of said legs, sets of contact springs and an armature formed of para-magnetic material and disposed for rotation between said magnet legs and arranged to operate said contact springs, said armature having a portion continuously in engagement with one of said magnet legs and being supported to rotate about a line which is parallel to the longitudinal axis of the magnet legs and is also disposed in a plane passing through the centers of the said magnet legs, said line lying in a face of one of the magnet legs.

JOHN N. REYNOLDS.
